UNITED STATES PATENT OFFICE.

OGDEN A. WILLIAMS, OF NORTH LANSING, MICHIGAN.

FARM-GATE.

SPECIFICATION forming part of Letters Patent No. 373,116, dated November 15, 1887.

Application filed August 11, 1887. Serial No. 246,663. (No model.)

To all whom it may concern:

Be it known that I, OGDEN A. WILLIAMS, a citizen of the United States, residing at North Lansing, in the county of Ingham and State of Michigan, have invented certain new and useful Improvements in Farm-Gates, of which the following is a specification, reference being had therein to the accompanying drawings.

This invention relates to certain new and useful improvements in farm-gates.

The object of the invention is to construct a farm-gate that can readily be vertically raised or adjusted in order to clear obstructions—such as snow in the winter—or to allow small stock to pass under it, while it prevents the larger animals from passing through. It is also designed to be so constructed as to relieve all lateral strain of the gate upon the post.

To this end the invention consists in the peculiar construction, arrangement, and combinations of the various parts, all as more fully hereinafter set forth.

Figure 1 is an elevation of my improved gate closed. Fig. 2 is a perspective view with the gate elevated so as to allow small stock to pass under it. Fig. 3 is a vertical section through the gate and its fastenings.

In the accompanying drawings, which form a part of this specification, A represents the hinge-post, and B the latch-post, of a gateway.

C is a heel-post, which is hinged to the post A, preferably by means of an "eye-and-staple" hinge, as shown.

E is a slatted gate the upper and lower rear corners of which are provided with brackets F and G, respectively, the former being provided with an anti-friction roller, H, which bears against the outer face of the heel-post C, while the latter is provided with a similar roller, I, which bears against the inner or opposite face of the heel-post. These brackets loosely embrace the heel-post, so that the gate can readily and easily be raised vertically, as hereinafter described.

At or about the longitudinal center of the gate a lever, J, is fulcrumed to the gate, its rear end being suspended by means of a link, K, from the upper end of the heel-post C.

The front stile of the gate, upon the same side with the lever, is provided with a series of stops, N, and with a guide rod or bracket, M,

between which and the gate the free end of the lever J projects and overlaps the latch-post B. This latch-post has projecting from it a series of flanged or shouldered stops, L, and upon referring to Fig. 2 it will be seen that these stops L are at different heights from the stops N on the gate.

As the weight of the gate is sustained by the lever J, I provide such lever with a truss-rod, O, which enables me to use a much lighter and less cumbersome lever than if such truss-rod were dispensed with.

In practice it will be seen that when the free end of the lever rests upon any one of the stops N the gate is prevented from sliding down to the ground, and may be freely swung upon its hinges. If it is intended to be left open, the lever should be detached from its rest and the gate allowed to drop to its lowest position, where it rests upon the ground. When the gate is closed from such open position, it will automatically latch itself. The free end of the lever striking the latch-post and being thrown off from the stop N it will be caught upon the stop L of the latch-post next below.

If it is desired to hold the gate in a higher or lower closed position for the purpose of providing egress under the gate for small animals, such adjustment is easily obtained by raising the free end of the lever from one stop to another stop, which movement carries the gate up vertically with it as the rear end of the gate slides on the heel-post, or the front end of the gate may be entirely dropped to the ground, if desired; and for this latter adjustment I preferably provide a slotted stop or shoe, P, near the latch-post, into which the free end of the gate fits when in such position.

By examining the drawings, Fig. 2, it will be seen that the weight of the gate is entirely supported by the lever, and as the two ends of the lever are respectively supported near the gate-posts the whole strain of the gate comes vertically upon the posts and is distributed between them, and, as the gate in its open position can be let down to the ground, the difficulty of counteracting lateral strain upon the hinge-post caused in other gates is avoided.

What I claim as my invention is—

1. In a farm-gate, the combination, with the hinge-post, of a heel-post hinged thereto and

- projecting above the same, a gate-frame having a vertically-sliding engagement therewith, a lever fulcrumed at or near the center of the gate-frame, a link suspending the rear end of said lever from the heel-post, a series of laterally-projecting stops on the front stile of the gate, and a series of laterally-projecting stops on the latch-post, all arranged substantially as described.
- 10 2. In a farm-gate, the combination, with the hinge-post, of a swinging heel-post hinged thereto and projecting above the same, a gate-frame having a vertically-sliding engagement therewith by means of brackets and friction-rollers, a hanger between the rear end of said lever and the top of the heel-post, a series of laterally-projecting stops on the front stile of the gate, and a series of laterally-projecting shouldered stops on the latch-post, all substantially as and for the purposes described.
- 15
- 20

3. In a farm-gate, the combination of the hinge-post A, latch-post B, swinging heel-post C, gate-frame E, brackets F and G, rollers H and I, lever J, link K, stops L and N, projecting laterally from the latch-post and gate, respectively, the guide-rod M on the front stile of the gate, and the shoe P, the parts being constructed, arranged, and operating substantially in the manner and for the purposes described.

30 In testimony whereof I affix my signature, in presence of two witnesses, this 30th day of July, 1887.

OGDEN A. WILLIAMS.
